UNITED STATES PATENT OFFICE.

JARROT L. ROLLINS, OF COLFAX, CALIFORNIA.

JAR-SEALING AND VACUUM-RELEASING DEVICE.

No. 876,591.

Specification of Letters Patent.

Patented Jan. 14, 1908.

Application filed May 7, 1907. Serial No. 372,352.

To all whom it may concern:

Be it known that I, JARROT L. ROLLINS, citizen of the United States, residing at Colfax, in the county of Placer and State of California, have invented new and useful Improvements in Jar-Sealing and Vacuum-Releasing Devices, of which the following is a specification.

My invention relates to a means for hermetically sealing jars, cans and like receptacles, and for readily breaking or releasing the vacuum within the jar so that it may be opened without difficulty.

It consists in the combination of parts, and in details of construction which will be more fully explained by reference to the accompanying drawings, in which—

Figure 1 is a plan or top view of the can, its top and sealing device. Fig. 2 is a vertical section of the same. Fig. 3 is a bottom plan view of a portion of the cover showing the passages 7. Fig. 4 shows a device to seat the cord. Fig. 5 is a section on line $x-x$ of Fig. 4. Fig. 6 shows the cord with the sealing material attached, ready for application to the jar.

In hermetically sealing jars and like containers, such jars have grooves or channels around the periphery at the top, and covers with flanges fit these grooves. Sealing material such as solder or wax in various forms, is then introduced, while the air is expelled from the jar by heat, to seal the jar and preserve its contents. Considerable difficulty is experienced in properly removing this sealing material, and admitting air, so that the cover can be readily removed to obtain access to the contents of the jar.

It is the object of my invention to provide an improved means whereby the sealing of the jar is effected without directly closing the channel and openings to the interior of the jar, and so that when the sealing medium has been removed, said openings are fully exposed and the channel substantially cleared of the sealing medium.

A represents a jar, can, or other receptacle of any desired shape and material. This jar has an annular grooved or channeled flange 2 at the top, the inner side of the channel being approximately vertical, and the outer side beveled or inclined so that in cross section the groove is V-shaped in appearance.

The cover B has a downwardly projecting circumferential flange 4 which is adapted to

enter the groove or channel of the jar, the inner periphery of the flange lying close to the inner shoulder of the channel, so that when the cover is in place, a substantially V-shaped groove will be exposed outside of the periphery of the cover flange, and between it and the inclined side of the channel of the jar flange.

The inside of the cover flange may have grooves or channels 7 extending through it and communicating with the interior of the jar.

The sealing device consists of a cord 5 which may be made of manila, hemp, cotton, or other fabric, of such diameter as will fit within the V-shaped channel exterior to the cover flange. This cord may be made of such length as to coil once or twice around within the channel, and preferably has a sufficiently greater length, so that it may be brought across the top of the cover, as shown at 5^a. The cover may have one or more grooves or channels formed radially, or otherwise, in its outer surface within which the cord will lie depressed and out of the way, and by making a depression or groove 8 transversely across this cord-retaining channel, the cord will be sufficiently exposed at that point, so that the thumb and finger may be used to grasp it, and pull it out of its place, and out of the sealing channel. This cord may, if desired, have a thin wire core which will stiffen it sufficiently so that when the cord has been prepared and coiled to the proper size to fit the channel around the jar, it will remain sufficiently rigid to be applied, but the sealing coating is ordinarily sufficient. It is thus possible to prepare a large number of these sealing devices to be used on jars or cans having the sealing channel of any diameter, and such cords may be prepared and kept in readiness for work upon various sized jars.

The cord is prepared by incorporating some waxy substance with its fiber, preferably by immersing it in the melted wax or material; then stripping and pressing any excess of wax from it so that substantially no wax adheres to its exterior, and in this state it would not be suitable for sealing. A rubber coating might also be applied. The cord thus treated is placed in a form or groove of the size of the groove in the jar upon which it is to be used, and is then pressed into this groove. The end which is to be subsequently used for detaching the cord, being extended

from the groove, and preferably toward the center of the ring so as to fit its subsequent position upon the jar, as previously described.

The cord having thus been fitted to the 5 groove, and pressed to the bottom thereof, is coated with melted wax or sealing material, which forms a top adherent to the upper surface of the cord, as shown at 6. The wax only covers that portion of the cord lying 10 within the groove, the extension being left in its normal condition.

In order to seal one, or any number of jars, the fruit or other material is placed in the jar either cooked, or afterwards heated and 15 cooked and the air expelled in the usual manner. A ring is then placed in the groove between the outside of the cover flange and the interior beveled incline of the groove of the jar, with the free end of the string seated 20 in one of the grooves of the cover. The cord is seated in the sealing groove either by the fingers, or preferably by means of a seating device. Such a device is shown in Fig. 4, in which 9 is a flanged ring of such size as to fit 25 the top of the can, having upwardly extending arms 10 which arms are bent toward the center, and form or support a ring 11. Through this ring is slid able a stem 12 having at the lower end a ring 13. This ring is 30 of such size as to just fit the groove within which the sealing cord lies, and by pressing upon a handle upon the upper end of the stem, the ring 13 is caused to seat the sealing cord in the groove or channel.

35 A spring 14 may connect the exterior frame or standard with the slid able ring-carrying stem in such a manner as to normally raise it above the level of the can top, and it will be returned to this position by the 40 spring at any time after it and the compression ring have been pressed downward.

It will be seen from the peculiar structure of the sealing device that that portion of the cord which is substantially uncoated, is fitted 45 into the bottom of the V-shaped groove between the cover flange and the outer channeled rim of the jar, and the heat derived from the jar, or otherwise applied, will melt the wax above the cord, thus forming a hermetical seal above the cord, and as the cord itself closes the air passages 7, it will be seen that no wax will enter to choke these passages; the wax or sealing medium forming a bridge above the cord, and effectually sealing 55 the jar when it has sufficiently cooled to allow the medium to harden. In order to open or unseal the jar, it is only necessary to grasp the exposed part 5^a of the cord, and strip it out of the groove in which it rests. 60 This breaks and tears away the superposed wax, thus clearing the groove, and when the cord has been removed from the groove, the unsealing opening 7 will be exposed so as to allow air to be admitted and the vacuum 65 broken, after which the top may be readily

removed. By this method of sealing, I prevent the sealing medium from filling and adhering to the lower part of the groove of the jar, and insure its being substantially stripped out to leave the groove clear and the 70 vacuum breaking openings fully exposed.

It will be understood that in the preliminary treatment of the cord, it may be impregnated with a thin solution of rubber, in place of other material, and this will serve 75 equally well, and will also prevent the lower surface of the cord from adhering when the cord has been sealed in place.

Having thus described my invention, what I claim and desire to secure by Letters Pat- 80 ent is—

1. The combination with a jar or can and a cover therefor, said cover having a depending flange with grooves on the under side thereof connecting with the interior of the 85 jar, of a sealing medium for the cover, said medium including a flexible, compressible cord bent to fit the sealing groove of the jar, having its lower surface substantially non-absorbent and having a coating of sealing 90 material adherent to its upper surface.

2. The combination with a jar or can having a sealing groove or channel and a cover for the jar having a depending flange adapted to enter the groove of the jar, said flange 95 being provided with grooves in its underside leading to the interior of the jar, of a sealing medium, said medium consisting of a substantially flexible compressible cord coiled to fit the sealing groove or channel of the jar, 100 with its lower surface substantially non-adherent, and its upper surface carrying a fusible sealing material of such length as to fill the groove of the jar, said cord having an uncoated extension capable of extending 105 across and being seated upon the jar cover.

3. A jar and can sealing and unsealing device consisting of a coiled flexible cord having a semi-coating of fusible sealing material, a jar having a groove around its periphery, a 110 cover having a flange fitting the inner portion of the groove, and having channels made to communicate with the interior of the jar, said cord being seated in the bottom of the groove and covered by the fused and subsequently hardened medium, and means by which the cord and sealing medium are removed to expose the channels.

4. A jar or can having a peripheral groove or channel at the top, with the outwardly inclined outer wall, a cover having a flange fitting the inner portion of said groove, said flange having openings communicating with the interior of the jar, a compressible cord fitting the groove or channel, having its 115 lower surface substantially non-adherent, and the upper surface carrying a coating of sealing material, and an extension of said cord whereby it may be removed from its seat. 120 125 130

5. A jar or can having a peripheral groove around its top, a cover having a flange fitting the inner portion of said groove, and forming therewith a V-shaped channel, said flange 5 having channels in its underside leading to the interior of the jar, and said cover having grooves formed in its top, a compressible cord bent to fit the circumferential groove of the jar, said cord having its lower surface 10 non-adherent, and a coating of fusible sealing material upon its upper surface filling the

circumference of the groove, said cord having an uncoated extension seated in one of the grooves or channels on the top of the cover.

In testimony whereof I have hereunto set 15 my hand in presence of two subscribing witnesses.
